UNITED STATES PATENT OFFICE.

WILLIAM F. HAJEK, OF CHICAGO, ILLINOIS.

FIRE-ESCAPE.

1,084,737.

Specification of Letters Patent.

Patented Jan. 20, 1914.

Application filed December 7, 1912. Serial No. 735,373.

To all whom it may concern:

Be it known that I, WILLIAM F. HAJEK, a citizen of the United States, and a resident of the city of Chicago, in the county of Cook and State of Illinois, have invented certain new and useful Improvements in Fire-Escapes; and I do hereby declare that the following is a full, clear, and exact description of the same, reference being had to the accompanying drawings, and to the numbers of reference marked thereon, which form a part of this specification.

This invention relates to improvements in fire escapes of that class set forth in my prior application for patent for "fire escapes", filed on the 19th day of August, 1912, Serial No. 715,768, and in which an extensible fire escape ladder was provided normally concealed within a recess in the wall adjacent or beneath each window in position to be projected into supporting position by the occupant of a room when emergency demands. In such constructions, where buildings are of considerable height, the space available beneath or adjacent the window may be insufficient to afford convenient storage space for the ladder when folded from use, and in consequence, it may occur that a ladder may prove too short to reach the ground for safety. In such instances it is true the user of the ladder might, if instructed, enter the lower window and project the ladder from that floor height if the conditions made the same possible, or might even, if informed, project the ladder from such lower floor height while supported adjacent thereto on the ladder previously brought into use. In times of excitement, however, it is desirable that in the event of it becoming necessary to use such a device, a line of escape may be afforded from the topmost story to the ground, whereby the occupant may escape from any of the floors of the building.

The object of this invention is to afford a fire escape of the class described whereby the release of the fire escape from any floor will immediately project the fire escape from all the floors for that line of windows or wall openings to afford an avenue of escape from all the floors.

It is an object of the invention to afford a construction of the utmost simplicity and

durability, incapable of getting out of order and of such a nature as to constantly and 55 instantly be ready for use, and whereby the necessity for the construction of external and permanent fire escapes may be obviated.

The invention (in a preferred form) is illustrated in the drawings, and hereinafter 60 more fully described.

In the drawings: Figure 1 is a fragmentary inner front view of a device embodying my invention, illustrating the same for two story heights. Fig. 2 is a fragmentary section taken at a right angle with that shown in Fig. 1. Fig. 3 is an enlarged detail view of the mechanism for simultaneously releasing all the ladders. Fig. 4 is a section on line 4—4 of Fig. 3. Fig. 5 is a fragmentary 65 detail illustrating the connection between the actuating shaft and the releasing shaft. Fig. 6 is an enlarged fragmentary detail section showing the ladder stored within its recess. Fig. 7 is a similar view, showing the 70 ladder discharged therefrom and released for use. Fig. 8 is an enlarged fragmentary detail of the ladder. Fig. 9 is an enlarged, 75 fragmentary edge view of the ladder, showing it closed. Fig. 10 is an enlarged, fragmentary detail of the hinged connection between the toggle connecting links. Fig. 11 is an enlarged section on line 11—11 of Fig. 6. Figs. 12 and 13 are enlarged, fragmentary details on line 12—12 and 13—13 of 80 Fig. 6, with parts omitted. Fig. 14 is a fragmentary section of one of the rods connecting the chains which support the ladder 85 within the wall recess.

As shown in the drawings: Each window 90 for the entire height of the building is provided with an outwardly opening recess therebeneath, which is closed on the inner side by a suitable metallic or other convex casing 1, rigidly secured to the wall, which 95 projects upwardly to close against or beneath the inner sill of the window. Rigidly secured on the inner face of the wall is an attaching plate 2, which projects upwardly to partly cover or close the inner end of said 100 recess and secured to which near each end of the recess are chains or fireproof cables 3, connected at each end in which, at suitable intervals apart, are rods or rounds 4, each provided at its outer end with a roller 5, 105 adapted to travel on the web of an angle

bar 6, which are pivoted at their inner ends adjacent to the inner end of each recess, as indicated at 7, and are free to swing outwardly as shown in Figs. 7 and 13, when said chains are drawn outwardly.

Secured on, and depending from the outermost round 4, by means of chains or fire-proof cables 8, is a step or transverse member 9, constructed of light, and relatively narrow channel bars, the flanges of which are turned downwardly and which is much shorter than said wall recess, and beneath which, and suspended on which at equal intervals apart, one upon another by means of links or toggle bars 10 and 11, are similar steps 9, of a number sufficient to extend at least to the sill of the next succeeding window below that from which the ladder thus formed, extends. Said toggle bars, as shown, are pivotally engaged together intermediate the steps or transverse members 9, and the extremity of each is provided with a lip 12, which engages over the back of the next to hold the same in alinement and prevent unnecessary lateral swinging during their use as a ladder. The lowermost or outermost of said transverse members or steps 9, is secured through the medium of the link depending therefrom, to a weight 13, of a length and width adapted to fit in, and close said recess from the outer side, said weight closing closely beneath the sill and at its lower, relatively thin edge, fitting into a recess in the wall, as shown in Fig. 6. The upper edge of said weight when so arranged to close the recess, projects beyond the line of the building wall so that the same is normally in unstable equilibrium, and an upwardly directed hook 14, is provided on the inner face of said weight near the top thereof near each end of the same. A tripping lever 15, is pivoted on the wall in each end of said recess near the top of the same, and is provided with an outer hooked end adapted to engage the hook 14, on said weight, and at its inner end projects beneath a shaft 16, journaled transversely at the inner side of the wall and beneath the window ledge or sill, and provided with an eccentric or cam 17, which bears upon said lever and which, when the shaft is rotated, acts to raise the outer end of the lever to release the weight. At one extremity said shaft is provided with a bevel gear 18, which meshes with a bevel gear 19, on a vertical shaft 20, which extends for the entire building height and at each window is provided as before described, with a bevel gear entrained to actuate the releasing shaft for the fire escape for that floor. Said shaft at a point above each floor, extends through a box 21, closed at its inner side with a glass front 22, through which said shaft may be seen, and engaged on said shaft is a ratchet lever 23, accessible when

the glass is broken and whereby the shaft may be rotated by the occupant of the room sufficiently to actuate all the releasing shafts for that line of windows to permit the release of the fire escape. As shown, a shaft 26, extends transversely said recess or compartment beneath each window, and well above the chains and channel bars and pivotally engaged at the inner end thereon at each end of the recess, is a slide plate 27, of a length to extend to near the outer edge of the wall.

The operation is as follows: The ladders are stored within the compartment beneath each window by first adjusting the releasing shaft 16, to bring the eccentrics out of engagement with said levers and by drawing inwardly on the chains and rounds and folding the channel bars 6, inwardly, as shown in Fig. 6, then telescoping and folding the ladder sections, as shown in Figs. 6 and 11, and storing the same in an inclined position upon the slide plates 27. The weight is then drawn upwardly and is seated to close the aperture from the outer side, the tripping lever 14, engaging the hook 13, thereon and positively supporting said weight from accidental release. The ratchet lever 23, whereby the main actuating shaft is employed, is protected from interference in the box 21, before described. It, however, is instantly accessible when emergency demands by the breakage of the glass front of the box and the occupant of any of the rooms then seizes the ratchet lever and rotates the vertical shaft thereby, a quarter turn being sufficient to bring the eccentrics on the tripping shafts into actuating engagement with the tripping levers to release the weight 13. The weight then being in unstable equilibrium, falls outwardly from the building and in so falling, acts as a lever as it swings outwardly from the building to start the outward movement of the ladder, which is thus projected bodily out of the aperture and is extended by the weight, simultaneously swinging the channel bars 6, outwardly to afford ways to project the ladder free from the wall. The single operation by the occupant of the room has thus been sufficient to project all the ladders for that line of windows from the top to the bottom of the building, outwardly to afford a continuous line of descent, down which escape may readily be effected.

Of course, while I have shown channel bars as affording the steps of the ladder, it is to be understood that any suitable form of step may be used, whether in the form of a structural bar or otherwise, and while I have shown chains as employed in a part of the construction, it is understood that any fire-proof cable or flexible material may be used, it being important only to use such material as will not be rendered ineffective or useless by fire.

Of course, it is to be understood that details of the construction may be varied. I therefore do not purpose limiting the patent granted on this application otherwise than necessitated by the prior art.

5 I claim as my invention:

1. In a device of the class described a collapsible fire escape ladder retained in a recess in a wall of a building, chains secured 10 to the upper end of said ladder, rollers on said chains, track members pivotally connected at their ends in said recess and adapted to swing outwardly with the ends thereof projecting beyond said recess and rollers 15 on said chains adapted to track on said pivotally members to facilitate extension of the ladder into operable position.

2. In a device of the class described a collapsible ladder contained in a recess in the 20 wall of a building, chains at the upper end of said ladder and secured to the wall within recess, rollers on said chains, tracking members for said rollers pivotally mounted at their ends adapted to fold toward one another when in position out of use, a slide 25 plate pivotally mounted above said track members to receive said folded ladder thereon in inclined position, and a releasing member adapted to release said folded ladder to 30 permit ejection thereof from said recess, said track members acting to swing outwardly and support said ladder away from the walls of the building.

3. In a device of the class described a 35 building having recesses in the walls thereof, collapsible ladders folded therein, a pivotally plate supporting said ladders in said recesses in inclined position, a weighted closure for the outer side of each recess, 40 means retaining said weighted closure in position with the ladder within the recess, tracking members pivotally mounted beneath said pivotally plate, and mechanisms adapted to actuate said means for said closure to permit the 45 same to fall outwardly to extend the ladder, said tracking members adapted to be swung outwardly to support said extended ladder away from the walls of the building.

4. In a device of the class described a foldable ladder, a chain securing the same within 50 a recess in the walls of a building, rollers on said chain, pivotally mounted angle irons adapted to fold inwardly toward one another within said recess when out of use, a pivotally plate for supporting said ladder in 55 inclined position above said track members, and means releasing said ladder to extended position, said tracking members swinging outwardly to support the chain and maintain the ladder in a position away from the building.

5. In a device of the class described a pivotally plate contained within a recess in a building, a foldable ladder mounted thereon, a weight attached to the lower end of

said ladder and adapted to close the recess in said building, a lever actuatable from the interior of the building adapted to retain said closure in place, a chain securing the inner end of said ladder within the recess 70 in said building, and foldable tracking elements, one on each side of the recess, adapted to unfold when said ladder is extended to afford tracking means for said chain and support said ladder in extended position 75 away from the walls of the building.

6. In a device of the class described a collapsible ladder contained in a recess in the walls of a building, a pivoted plate adapted 80 to support the same therein in inclined position to facilitate projection thereof from said recess, a weight attached to the outer end of said ladder and serving to close the recess in the wall of said building, means releasing said weight to automatically extend 85 said ladder, and tracking means pivotally mounted beneath said pivoted plate and adapted to swing outwardly beyond the walls of the building to maintain said ladder spaced therefrom when in extended position. 90

7. In a device of the class described a plurality of simultaneously actuatable and cooperative ladder sections, each one comprising a foldable ladder, chains securely connecting the same with a building, and pivotally means, one for each of said ladder 95 chains adapted to swing outwardly away from one another to guide said chains and to support said ladder sections away from the building.

8. In a device of the class described a collapsible ladder concealed in a recess in the wall of a building, a weight on the end thereof affording a closure for said recess, a plate supporting said ladder in folded position inclined within said recess, a chain connecting the inner end of said ladder with the walls of the building, rollers on said chain, foldable tracking means for said rollers to support said ladder in extended position away from the walls of a building, and cam actuated releasing means for said weighted closure which, when actuated, permits the gravitational extension of said ladder.

9. In a device of the class described a foldable ladder concealed in a recess in a wall of a building, chains connecting said ladder to the building within said recess, rollers on said chains, and a plurality of pivotally mounted track members within said recess adapted to receive said rollers when the ladder is extended, and serving to maintain the same projected away from the wall of the building in such position.

10. In a device of the class described a ladder comprising rungs, hingedly connected side members supporting the same, and adapting the same to be folded in close relation with one another, pivotally means sup-

porting the ladder in inclined position in a recess in the wall of a building, a pivoted lever adapted to hold said ladder within said recess, a rotatable shaft adjacent said lever, and a cam thereon adapted to contact said lever to actuate the same into releasing position when said shaft is rotated.

In testimony whereof I have hereunto subscribed my name in the presence of two subscribing witnesses.

WILLIAM F. HAJEK.
